Patented June 6, 1922.

UNITED STATES PATENT OFFICE.

GEORGE C. NETH, OF DAYTON, OHIO.

METAL-CUTTING-MACHINE TOOL.

1,418,727.

Specification of Letters Patent. Patented June 6, 1922.

Application filed July 14, 1920. Serial No. 396,132.

To all whom it may concern:

Be it known that I, GEORGE C. NETH, a citizen of the United States, residing at Dayton, in the county of Montgomery and State of Ohio, have invented certain new and useful Improvements in Metal-Cutting-Machine Tools, of which the following is a specification.

This invention relates to new and useful improvements in metal cutting tools adapted to be used in connection with lathes, planers, shapers and the like. The object of the invention is to provide a tool of the above type by means of which the work may be machined accurately. To the above end the device is simple in construction and efficient in operation.

Referring to the accompanying drawings Fig. 1 is a plan view; Fig. 2 is a side elevation; Fig. 3 is a section on the lines 3—3 of Figs. 1 and 2; Fig. 4 is a section on the line 4—4 of Fig. 1; Fig. 5 is a section on the line 5—5 of Figs. 1 and 2; and Figs. 6 to 9 inclusive are detail views of the resilient plugs which form a part of the tool.

Referring more particularly to the drawings—1 represents a shank having a head —2. The head —2 is provided with an opening or orifice —3 adapted to receive a bit —4. The bit —4 provides the cutting edge —5, which may be of various shapes. The opening or orifice —3 is of such a shape that it is adapted to receive either a square or a round bit. The bit is held within the opening by a set screw —6. To provide a resilient mounting for the bit, the head —2 is provided with a kerf —7 which provides a resilient portion —8 in the head. This resilient portion of the head allows the tool to recede whenever the tool strikes a hard spot in the metal. To augment this resilient portion, commensurate with the metal worked upon, and the accuracy of work desired, the head, at the upper end of the kerf —7, is provided with an orifice —9 adapted to receive

plugs —10 of various resiliency. The plugs —10 are provided with a central opening —11 and a kerf —12. The openings —11 are of various diameters thereby varying the resiliency of the plugs. The plugs —11 may be easily driven in and out of the orifice —9 and are held therein by a drive fit. The plugs —10 and the resilient portion —8 are disposed perpendicularly to the cutting line of the tool, therefore, the receding movement of the bit —5 will be away from the work or in line with or parallel to the cutting line. This disposition of the plugs and portion —8 prevents the bit moving laterally, thereby eliminating the possibility of inaccurate work. The tool is particularly adapted to be used in machining grooves and slots such as screw threads. The bit —5 is disposed at an angle to the shank —1, which permits the orifice —3 to be open at both ends and eliminates excess metal in the head —2. The shank —1 is adapted to be received by the conventional tool holder —13 of the lathe, planer or shaper in a well known manner.

Having described my invention I claim:

In a device of the character described, a wedge shaped head, a shank extending from the wide end and in alinement with one side thereof, said head having an opening adapted to receive a cutting element lying parallel with the other side of said head and at an angle to said shank, means for holding said cutting element in said opening, said head having a kerf and a socket extending across the wide portion thereof, said kerf opening through the under side thereof, lying at a right angle to the opening for the cutting element and permitting the forward portion of the head and the cutting element to yield, said socket being adapted to receive bushings of different resiliency.

In testimony whereof I affix my signature.

GEORGE C. NETH.
